GRINDING MACHINE

Christy A. Wiken and Eric A. Reibig, Milwaukee, Wis., assignors, by mesne assignments, to Rockwell Manufacturing Company, Pittsburgh, Pa., a corporation of Pennsylvania

Application June 22, 1943, Serial No. 491,824

9 Claims. (Cl. 51—123)

1

The present invention relates to machine tools and is more particularly concerned with grinding machines having a device for carrying a rotary tool, supported on centers, past a grinding wheel for sharpening the cutting edges, although it is not limited to such use, inasmuch as certain features are capable of advantageous utilization in other machines.

Although machines of this general character have been heretofore proposed, and some of them have gone into use, they are complicated and costly, and moreover are of special construction, embodying a permanent headstock and tailstock assembly adapting the machines solely to the grinding of work between centers, and by reason of their design they cannot be successfully utilized to carry out other grinding operations. It has accordingly been impracticable for the owner of a small shop to make the substantial investment required to purchase the prior tool and cutter sharpening machines, especially since they would be idle except when tool or cutter sharpening jobs were actually being carried out. Small shops have therefore sent out their tool and cutter sharpening work to shops having special machines designed for that purpose.

It is accordingly the primary object of this invention to provide a grinding machine having a tool holder assembly for carrying a tool or cutter past the grinding wheel, which will accurately hold the tool in proper position during grinding, permits readily indexing of the tool, to successively present its cutting edges of the wheel, and is so designed that the tool holder assembly may be completely removed and the machine employed for surface or other classes of grinding operations.

A further important object is to provide a tool holding and centering device which is so designed that it may be installed on the tables of existing grinding machines as an attachment, will rigidly and accurately hold tools in proper grinding position, may be readily removed to restore the grinding machine to its original condition, and yet which is of low cost, rugged construction.

Another object is to provide an auxiliary table assembly, embodying centers for holding a tool, with a pilot assembly adapting it for secure mounting on the tables of existing grinding machines, in any one of a plurality of angular adjusted positions about an axis normal to the table surface, for sharpening tools having differently inclined cutting edges.

A further object is to provide an auxiliary table adapted to be installed on the flat table of exist-

2

ing grinding machines and having flat accurately-formed bearing surfaces on its lower side adapted to rest on the table and a flat top bearing surface on its upper side adapted to adjustably support a headstock and a tailstock, the bearing surfaces lying in parallel planes and the auxiliary table having no portions lying outside those planes, whereby the table may be accurately finished in a simple surface grinding operation, eliminating hand finishing.

Another object is to provide a tool holding assembly embodying a headstock and a tailstock which are of substantially identical construction, it being only necessary to interchange certain minor parts to convert one to the other.

A further object is to provide a grinding machine, having a table movable in a horizontal plane under the wheel, with a novel guard assembly, embodying an adjustably pivoted arm and a plurality of guards adapted for interchangeable installation on the arm, so as to efficiently guard the wheel irrespective of the type or size of wheel that may be installed in the machine.

The invention further aims to provide a tooth stop device comprising a novel assembly of parts which may be interconnected in a plurality of different relationships to correctly cooperate with the teeth or other projections of the various types and sizes of tools or cutters to be ground, and yet which permits ready indexing of the tool to successively present its cutting edges to the grinding wheel.

Another object is to provide a grinding machine, having a table reciprocable with respect to the wheel, with a center device for holding a tool, and a tooth stop device for successively stepping the tool about its axis to present its cutting edges to the wheel and to provide means for mounting the tooth stop device either stationarily upon the machine or upon the reciprocable table, to achieve the desired tooth-stopping action.

Additional objects are to provide improved headstock and tailstock assemblies, and other grinding machine improvements and refinements to be hereinafter pointed out.

Further objects will become apparent as the specification proceeds in conjunction with the annexed drawings, and from the appended claims.

In the drawings:

Figure 1 is a perspective view of the grinding apparatus of the invention, showing a side milling cutter in grinding position thereon;

Figure 2 is a similar view of the apparatus, showing a hand reamer in place on the machine;

3

Figure 3 is a front elevational view of the wheel guard mounting frame, showing a small diameter cup wheel guard in operative position thereon;

Figure 4 is a vertical sectional view through the guard and mounting assembly of Figure 3, looking in the direction of the arrows, the wheel being shown in broken lines;

Figure 5 is a view similar to Figure 3, but shows a large diameter disc wheel guard in place;

Figure 6 is a vertical sectional view through the apparatus of Figure 5;

Figure 7 is a top plan view showing the auxiliary table assembly of the invention in place on the main grinder table, with parts broken away and in section to more clearly illustrate the structure;

Figure 8 is a front elevational view of the device shown in Figure 7, parts being broken away and in section to illustrate certain details of the structure;

Figure 9 is a vertical sectional view on an enlarged scale, taken substantially on the line 9—9 of Figure 8;

Figure 9a is a fragmental sectional view illustrating the manner in which the tailstock is guided on the auxiliary table;

Figure 10 is a vertical sectional view on an enlarged scale, taken substantially on the line 10—10 of Figure 8;

Figure 11 is an exploded view of the parts of the tooth rest of the invention;

Figure 11a is a perspective view of a modified form of stop finger for use with the assembly of Figure 11;

Figure 12 is a longitudinal sectional view illustrating certain parts of the tooth rest;

Figure 13 is a perspective view showing a spiral cutter mounted on the apparatus of the invention by means of a mandrel;

Figure 14 shows the machine with the side milling cutter of Figure 1 in place thereon, but illustrates the parts from a different angle;

Figure 15 is a perspective view showing the side milling cutter of Figures 1 and 14 in place on the machine, and with the auxiliary table swung through 45° to present the bevel side edges of the cutter to the wheel;

Figure 16 is a perspective view of the device shown in Figure 15;

Figure 17 is a perspective view with a form cutter in place on the machine of the invention and with a dish wheel and dish wheel guard installed;

Figure 18 is a side elevational view, with parts in section, of a headstock of modified form, also forming part of the invention;

Figure 19 is a view similar to Figure 18 showing a modified form of tailstock also forming part of the invention;

Figure 20 is a top plan view with parts broken away and in section showing the auxiliary table equipped with a fine adjustment device forming part of the invention; and

Figure 21 is a vertical sectional view through the device of Figure 20.

With continued reference to the drawings, wherein like reference characters have been employed to designate similar parts throughout the several views thereof, and referring first to Figure 1, the grinding machine to which the invention has been applied comprises a base 9, carrying an upright column 11, on which a grinder head 12 is mounted for vertical adjustment by means of a screw 13 and a hand wheel 14. Mounted for rotation in a grinder frame 10, which is rockably carried by head 12, and driven by a motor (not

4

shown) is an arbor assembly 16, carrying a grinding wheel 17, a cup type grinding wheel being shown installed in Figures 1 and 2. A micrometer screw 18 is employed to adjust grinding frame 10 up and down with respect to head 12.

Mounted for movement in a horizontal plane toward and away from column 11 is a table slide 19, adapted to be actuated by a hand wheel 21, the latter being carried by a screw (not shown) which is threadedly connected to the table slide. Mounted for sliding movement on the table slide at right angles thereto, and actuated by means of a hand wheel 22, is a table 23, having a flat work supporting surface 24 and a longitudinal T-slot 25.

Movement of table 23 is limited in both directions by means of a pair of stop brackets 26 carried by a rod 27 mounted on the table, and co-operating with a stop screw 28 carried by a boss 29 on slide member 19.

The grinder structure so far described is fully disclosed and claimed in our co-pending application, Serial No. 467,512, filed December 1, 1942, for "Machine tools," which is now Patent No. 2,386,283, issued October 9, 1945, and which may be referred to for a more detailed disclosure thereof.

We have found that, by providing a pilot member A, rigidly anchored to the grinder table, and auxiliary table B, carrying a headstock C and a tailstock D, and mounting a tool rest assembly E upon either the auxiliary table or the main grinder structure, it is possible to convert the surface grinder of the aforementioned application, or similar grinders, into a tool and cutter grinder which will accurately sharpen a wide variety of tools, thereby obviating the necessity of purchasing a special machine and yet providing a structure which is of simple rugged design and which will turn out work of equal if not greater accuracy than the machines designed especially for tool and cutter sharpening purposes.

Referring to Figures 7 and 8, auxiliary table B is of elongated form and has a flat upper surface 31 and a ribbed and flanged lower surface.

Table B is preferably made of ordinary gray iron, and is of such design that the upper surface thereof may be finished in a simple surface grinding operation, there being no elements projecting above this surface. A longitudinal T-slot 32 extends longitudinally along the top of the table and is utilized to secure the headstock and tailstock in place in a manner to be hereinafter described.

The central part of the underside of the table is provided with a pair of ribs 33 and 34 defining a central space 35 to receive the pilot member A, and (as seen in Figure 7) the forward ends of ribs 33 and 34 are curved to lie substantially concentrically with the pilot member. A second pair of ribs 36 and 37 on the underside of the table, are concentric with the pilot member, and as seen in Figure 8 have their lower surfaces lying in a plane common with the lower edges of ribs 33 and 34. All of the foregoing bearing surfaces are adapted to seat snugly against the upper side of work table surface 24. Depending from one side of the auxiliary work table at opposite sides of the space 35 are flanges 39 and 41 and depending from the opposite side of the auxiliary work table are flanges 42 and 43, it being observed that ribs 33 and 36 merge into flanges 39 and 42 and ribs 34 and 37 merge into flanges 41 and 43. The ribs on the underside of the table also merge into a longitudinally extending

boss 44, which (as seen in Figure 9) provides the required metal for forming T-slot 32. By reason of the interconnected webs and ribs, and the fact that the lower surfaces of ribs 33, 34, 36 and 37 are utilized as bearing surfaces engaging the top of the work table, an extremely strong and rugged table unit is provided, and one which transmits the cutting or grinding forces to the main table in such manner as to avoid any strains that would result in distorting or "springing" the parts sufficiently to impair the accuracy of the apparatus.

In order to facilitate finishing of top surface 31 of the auxiliary table in a simple surface grinding operation, a pair of lugs 45 are cast on its lower side and have their lower surfaces disposed in the same plane as the bearing faces of the ribs. Accordingly, the auxiliary table may be so supported on the grinding machine during manufacture throughout its length by the ribs and lugs that it will not undergo distortion during the grinding operation. After manufacture of the table has been completed, lugs 45 may be removed if desired.

The novel manner in which the auxiliary table is held in place by the pilot member will now be described. Referring to Figures 7, 8 and 10, the pilot A is of generally disc-like form and is provided with a central opening 47 (Figure 10) and a cylindrical periphery 48, carrying graduations 49 (preferably being divided up directly into degrees running from zero to 45° in each direction from the zero or parallel position of the tables shown in Figure 8. The pilot member is secured to the main work table 23 by means of a pair of T-bolts 51 having heads seating in T-slot 25 of the table and projecting upwardly through diametrically spaced openings in the pilot member. A pair of nuts 52, seating in a pair of recesses 53 in the pilot member, are turned on the T-bolts and frictionally clamp the pilot member to the main table.

The pilot member is accurately positioned with respect to the main table by means of a pair of keys 55 secured in a longitudinal keyway 56 in the underside of the pilot member by means of cap screws 57 and projecting partially into T-slot 25 adjacent each T-bolt 51, as seen in Figures 8 and 10. Accordingly, by loosening nuts 52, pilot member A may be freely slid along the top of table 23, being guided by keys 55, and locked rigidly in any desired adjusted position by tightening nuts 52.

The auxiliary table is secured in place on the pilot member and work table in a manner seen more clearly in Figures 7 and 10. The auxiliary table and the pilot member are provided with aligned mating openings 59 and 61, respectively, and after manufacture and grinding of the auxiliary table is completed a trunnion or pivot plug 62 is frictionally fitted into opening 59 of the table, so as to pivotally project into opening 61 of the pilot member. If desired, the plug may alternatively be frictionally fitted into opening 61 of the pilot member and disposed in journaling relationship with opening 59 of the table.

From the foregoing structure it is apparent that the pilot member may be locked in the proper longitudinal adjusted position on the table, (preferably in the central position illustrated in Figure 8, so that all of the ribs (33, 34, 36 and 37) may bear upon the upper table surface) and may be locked in place by nuts 52. Also, the auxiliary table is accurately journalled for rocking movement about an axis normal to the table surface. The auxiliary table is adapted to

be frictionally clamped to the main table, in any desired angular position, as follows.

Projecting through a pair of openings 64 in the auxiliary table and a pair of arcuate slots 65 in the pilot member, and having heads 66 seating in arcuate counter bores 67 in the pilot member, are a pair of bolts 68. Nuts 69 on the bolts are adapted to pull the table down into tight engagement with the main table, it being observed in Figure 10 that when the parts are pulled up tight a clearance 71 exists between the lower face 72 of recess 35 of the auxiliary table, and the upper surface of the pilot. The provision of this clearance prevents the pilot from holding the auxiliary table with its bearing surfaces out of contact with the main table, it being understood that only a few thousandths of an inch clearance is necessary, and that if desired the clearance may be decreased by the use of shims. In order to locate nuts 69 below the top surface 31 of the auxiliary table, they are preferably disposed in recesses 73 at opposite sides of the table.

Secured to the front of the table adjacent front hold-down bolt 68, is a scale plate 75 by means of screws 76 having a reference line 77 cooperating with the graduations on cylindrical face 48 of the pilot member, it being understood that the holes in the plate are sufficiently oversize to permit the screws to be loosened and the plate adjusted by minor amounts in either direction to properly calibrate the machine, and when the adjustment has been obtained the screws are tightened to permanently lock it in position.

The auxiliary table is accordingly rigidly mounted upon the main work table, and by loosening nuts 69 the table may be rocked about the vertical axis of pilot trunnion 62, the desired angular position being secured by bringing the appropriate graduation on scale 48 into alignment with the zero reference line on plate 75. When the proper adjustment has been obtained nuts 69 are tightened, it being observed that, by reason of the clearance between the underside of the table and the pilot member, tightening of the nuts serves to directly pull the auxiliary table down into clamping engagement with the main table, with the bearing surfaces of ribs 33, 34, 36 and 37 in frictional locking engagement with the main table. The manner in which the tools or cutters are adapted to be mounted on centers and presented to the wheel will now be set forth.

Referring particularly to Figures 7, 8 and 9, tailstock D is provided with a flat face adapted for sliding engagement with the upper surface of the auxiliary table, and is guided for movement along it by a pair of keys 81 secured in a longitudinal recess 82 in the tailstock by a pair of screws 83, one key being located at each end of the tailstock. As seen in Figure 9a, keys 81 project into the upper part of T-slot 32 and are snugly guided therein so as to maintain the tailstock square with the auxiliary table.

The tailstock is adapted to be frictionally clamped to the upper side of the table by means of a single T-bolt 84, having a head seating in T-slot 32 of the auxiliary table, and a nut 85 bearing against the base of the tailstock. In order to line up the tailstock with the auxiliary table, it is provided with a pressure member 87 bearing against accurately formed faces 88 and 89 on the tailstock and the table respectively, it being observed in Figures 7 and 8 that, aside from the central break produced by front recess 73, surface 89 extends throughout the length of the table, so that pressure member 87 may cooperate

with it in any desired longitudinally adjusted position. A lug 91 is also provided on the tailstock adjacent the pressure member for preventing it from tending to rotate and rock the tailstock out of firm engagement with the table. The pressure member is held in place by means of a thumb screw 92 threaded onto a stud 93 secured in the tailstock base.

It is accordingly apparent that the tailstock may be slid into any desired position along the table and when the desired position has been attained thumb screw 92 is tightened, so as to cause the tailstock to be pulled toward the front of the table. This action causes keys 81 to engage the front wall of T-slot 32, taking up any lost motion between the keys and the slot and accurately aligning the tailstocks with the longitudinal axis of the table by a "T-square" action. Nut 85 is then turned home to rigidly clamp the tailstock in place.

Mounted for reciprocation in the upper end of the tailstock is a center 95, urged toward work gripping or loading position by a compression spring 96 seating against a cap 97 and adapted to be locked in place by a set screw 98. The center 95 is adapted to be retracted by means of an eccentric 99 seating in a transverse slot 101 in the center and carried by a shaft 102 having a reduced portion 103. The shaft is adapted to be locked in place by a set screw and lock nut assembly 104 having a reduced end seating in groove 103. The shaft is adapted to be rocked by means of a lever 105 secured to the end of the shaft. In the positions shown in Figure 8 the parts are in loading or work gripping position, and if desired screw 98 may be tightened to lock center 95. When it is desired to remove the work from the centers it is merely necessary to loosen screw 98 and rock handle 105 counterclockwise, which, through shaft 102, eccentric 99 and slot 101, retracts the center against the action of spring 96. A lubricant fitting 106 may be provided for admitting lubricant to the center and associated parts.

The headstock is supported upon and secured to the auxiliary table in a manner similar to the tailstock, and therefore similar reference characters, with the subscript "c," have been employed to designate the similar parts and they will not again be described. The headstock is provided with a simple cylindrical portion 108 in which a center 109 is adapted to be locked in longitudinally adjusted position by a set screw 111.

Referring particularly to Figures 3, 4, 5 and 6, and referring first to Figure 4, grinder frame 10 is provided with an end face disposed substantially normal to the axis of rotation of the wheel, designated as 112 in Figure 4, to which is secured, preferably by means of three screws 113, a dual purpose foundation or frame member 114, having a pair of arcuate slots 115 and 116 at its upper end and a pair of lugs 117 and 118 at its lower end. The lugs are reinforced by angular webs 119 and they are each provided with an opening 121 for receiving a tooth-stop supporting screw, as will be pointed out hereinafter. Adapted for interchangeable installation in either slot 115 or slot 116 is a bolt assembly 122 carrying a short crank arm 123 terminating in a forwardly directed pin or shaft 124. As seen in Figure 3, bolt 122 is provided with a square head 125 seating in an elongated recess 126 in crank arm 123, so that nut 120 may be loosened and link 123 slid and rocked into any desired position with respect to bolt 122, and then locked in place.

Pin 124 is preferably tightly fitted into link 123 so as to be non-rotatable therein and is adapted to interchangeably support any one of a plurality of wheel guards. This appreciably widens the scope of usefulness of the machine because it permits either cup, or dished or peripheral grinding wheels of different diameters to be installed, as well as affords a wide range of adjustability of the guards with respect to the wheel, depending upon the particular type of wheel guarding required by the work being handled.

In Figures 3 and 4 the guard of Figures 1 and 2 is shown in place on the machine, in proper guarding relationship to the wheel. The guard 15 comprises a guard portion 128 of generally semi-cylindrical form, having a front flange, and an ear 129 which freely fits over pin 124 and is adapted to be locked in place by a wing screw 131.

Referring to Figure 2, the parts are so adjusted 20 as to dispose guard 128 in comparatively close guarding relationship with wheel 17 and this relationship is also illustrated in Figure 13. In Figures 14 and 16, the guard has been removed and reversed end-for-end and reinstalled, with 25 the flange on the inside of the wheel, to make room for the tool in the particular grinding operation illustrated, it being understood that while lateral guarding of the wheel is no longer present, the cylindrical portion of the guard is still effective to guard the operator.

In Figures 5 and 6, the guard foundation assembly 30 is illustrated having a modified guard 133 installed thereon. A lug 134 on the guard fits over pin 124 and is locked in place by a wing screw 35 135, it being observed that nut 120 has been loosened and link 123 rocked upwardly into the position shown, to compensate for the increased diameter of the wheel and guard. The parts are then locked in place to securely hold the guard 40 in operative position with respect to the wheel. Referring to Figure 17, guard 133 is shown in proper guarding relationship to a dished form of wheel 17a, it being observed that the guard fits down closely around the wheel and that the front flange adequately guards the operator.

While any number of different size and type of guards may be provided for interchangeable installation on pin 124, the two guards shown have been found to take care of the various sizes and types of wheels generally used, and by reason of 50 the ready adjustability of the guard toward and away from the wheel to meet various grinding conditions, the reversibility of the guards and also the adjustability of the supporting arm, the wheel 55 may be efficiently guarded for all grinding operations.

The invention also embodies a novel work stop device adapted to cooperate with the teeth or other projections on the work and maintain it in 60 fixed angular relationship to the grinding wheel during the grinding operation, and yet permits ready indexing.

Referring particularly to Figures 11, 11a and 12, the device comprises a base member 141, having 65 a longitudinal slot 142 and terminating at one end in a head 143 having a pair of intersecting openings 144 and 145 which preferably are of the same diameter. A set screw 146 threaded into the head is adapted to lock a member placed in either aperture.

The base member is adapted to be secured in 70 place on various parts of the machine by means of a T-bolt 147 and a nut 148. For instance in Figure 2 the base is secured to the face of the auxiliary table by means of the bolt 147 seating

in the T-slot 32, while in Figure 13 the base member is secured to ear 117 of foundation member 114, so that the work is movable with respect to it.

Referring again to Figure 11, cooperating with head 143 of the base is a rod 149 having an enlarged end providing a transverse opening 151. Rod 149 may be mounted directly in opening 144 or 145 and locked in place by set screw 146. However, in handling certain classes of tool and cutter grinding, it is desirable to offset the rod from the base and we have accordingly also provided a pin 152 having a head providing a cross bore 153 of sufficient size to receive rod 145, and a threaded lower end 154. Rod 149 is adapted to be installed in bore 153 and pulled down into engagement with V-notches 155 in a collar 156 by means of a nut 157 threaded on the reduced portion 154 of pin 152, it being observed that the shank of the pin is of substantially the same diameter as openings 144 and 145, whereby it may be installed in either opening. In this instance, however, it is unnecessary to lock pin 152 in place with set screw 146, as the frictional force set up by nut 157 is usually sufficient to frictionally lock the parts.

Adapted to be inserted in opening 151 of rod 149, and locked in place by means of a set screw 158, is a rod 159 having a cross bore 161. Referring more particularly to Figure 12, rod 159 is adapted to snugly receive a thimble or sleeve 162 having a flange 163 into which a screw 164 is threaded. Mounted for sliding movement in sleeve 162 is the threaded shank 165 of a stop finger supporting head 166, the shank having a longitudinal groove or keyway 167 cooperating with a reduced end 168 of screw 164 to restrain it against rotation within the thimble. Threaded onto the shank is a nut 169, which bears against the upper face of flange 163 and is adapted to thread the shank upwardly in the thimble, the shank being shown in its lowermost position in Figure 12.

Head 166 is provided with a recess 171 and pivoted therein on a pin 172 is a finger supporting member 173. The finger support is urged in a clockwise direction by a spring 174, seating in recesses in the member and head 166, toward an adjustable stop screw 175 threaded into the head. Member 173 is also adapted to be locked against rocking movement by means of a set screw 177 threaded into head 166 and cooperating with a depression 178 in member 173.

Member 173 is adapted to interchangeably support either the straight finger 179 shown in Figure 11, or the hooked finger 181 shown in Figure 11a, the fingers being secured in place by a screw 182 threaded into the end of member 173.

Taking up the grinding operations illustrated in the several perspective views, we have shown in each instance a spacer block 190 interposed between the head and tailstock and the auxiliary table. Each block is provided with a rib on its lower face adapted to seat in the T-slot of the auxiliary table and has a longitudinal slot in its upper face adapted to receive the head and tailstock keys. In this instance pressure members 87 and 87c are mounted directly on the spacer blocks. While it is to be understood that blocks 190 need only be employed when large diametered work is being handled, they may, if desired, be left in place as permanent parts of the machine.

Referring first to Figure 2, the machine is illustrated as having a simple hand reamer 191 mounted in place between centers 95 and 109; the auxil-

iary table being set on "zero" so as to move the tool edges to be ground exactly parallel to the path of travel of the main table; and the straight finger stop 179 is shown as cooperating with the teeth of the reamer for stepping it around as the grinding operation proceeds. Stops 26 are so adjusted on rod 27 as to cause stop pin 28 to limit the travel of table 23 to that required to grind the tool. The head and tailstock and spacer block assemblies are secured to the table by bolts somewhat longer than those shown in Figures 8 and 9.

In this instance base member 141 is clamped directly to the top of the auxiliary table by bolt 147 and rod 159 is clamped directly in opening 145 by means of set screw 146. The stop assembly is directly carried by rod 159 and is so oriented as to be stopped by screw 175 when the finger pivots toward the front of the machine, with the result that the operator, with each passage of the work need only rotate the reamer an angular distance corresponding to one tooth space, and during this "indexing" operation the reamer will pivot the finger outwardly against the action of spring 174 into the proper position to stop the next tooth or cutting edge in the proper grinding position. It is to be understood that, if the work is not properly ground by single passage across the wheel face, handwheel 21 may be rotated to move slide table 19; work table 23; and auxiliary table B bodily toward the grinding wheel by the necessary distance to take off the required amount of metal to restore the cutting edges of the tool. It is to be understood that during grinding the operator will grasp the work and urge it into firm contact with the stop.

As is well understood in the grinding art, it is often desirable to cut with only a portion of the wheel face, the grinding face often being tilted from one-half to one degree from the plane of the surface being ground, which prevents the back edge from dragging; eliminates any possibility of burning, and results in a much better job. In the present machine this cocking or tilting of the wheel is effected by loosening the bolt for the column and turning the column through the required angle (usually from one-half to one degree) to incline the wheel face at a similar angle with respect to the path of travel of the main table.

It should be observed that in this particular setup of the tooth stop, neither rod 149 nor pin 152 and its associated parts is employed. The number of parts employed in any case will depend upon the conditions of each setup, and there is of course no hard and fast rule as to how they will be arranged. The invention, however, in providing the novel assembly of parts illustrated provides a sufficiently flexible assembly to meet any desired setup, it merely being necessary to arrange them in the proper relationship to achieve the proper work-stopping action.

Referring to Figures 1, 14, 15 and 16, we have illustrated the machine setup to sharpen a side milling cutter 193, having side cutting edges 194 and peripheral cutting edges 195 and 45° bevel corners 196, the parts being shown in Figures 15 and 16 in proper position to grind the 45° corners and in Figures 1 and 14 in position to grind the peripheral edges 195.

Referring first to Figures 1 and 14, the auxiliary table is set on zero, so that it will move parallel to the plane of the wheel. Guard 128 has been removed and replaced in reversed position on shaft 124, and spacer blocks 190 are again used to raise the head and tailstock the proper dis-

11

tance to provide the required swing of the tool. Base member 141 of the finger stop assembly is secured directly upon the auxiliary table by means of bolt 147 and nut 148 and in this instance rod 159 is mounted directly in opening 145 of the base and locked therein by screw 146. Rod 159 carries thimble 162 of the stop assembly, and in this instance the hook form of stop 181 is secured to carrier 173 in an inclined position, so as to lie directly under the tooth being ground. The head 166 is so disposed that arm 173 is freely pivotal toward the wheel, so that upon completion of the grinding of one face the tool may be rotated clockwise (Figure 14) to bring the next face into grinding position, it being understood that in all of the grinding operations, the operator will exert sufficient pressure upon the tool to maintain the "stopped" tooth in firm engagement with the tooth stop, thereby predetermining the amount of metal the wheel will remove from each tooth.

When all of the peripheral edges 195 have been sharpened in the manner just discussed, the parts are then brought into the relationship shown in Figures 15 and 16, as follows. The tool and mandrel are removed from the centers and reversed end-for-end, so as to incline the teeth upwardly adjacent the wheel; nuts 69 are loosened and the table rocked 45°, as determined by the graduations on scale plate 75. It is also desirable to recombine the parts of the tooth lock device as follows. As seen in Figures 15 and 16, base 141 is clamped to the auxiliary table in reversed position from Figure 14, and pin 152 is inserted in opening 145 in the base and rigidly clamps rod 159 by means of collar 156 and nut 157. Hook finger 181 is inclined as before, but in this instance engages the top of the teeth as they are successively brought into grinding position and it is accordingly necessary for the operator to exert a clockwise rotative force upon the tool during the grinding operation.

When it is desired to grind the tapered corner 196 on the other side of the cutter, it is merely necessary to rock the auxiliary table to its opposite 45° limiting position and to move the tooth stop finger assembly onto the other side of the tool.

In Figure 13 there is shown a helical cutting tool 201 carried by a mandrel 202 between the centers in operative grinding relationship with wheel 17. In this setup of parts the auxiliary table is again set on zero, so as to travel exactly parallel with the cutting face of the wheel, but as the teeth 203 of the cutter are of helical form and must be rocked during grinding, a somewhat different stop arrangement is employed.

Base member 141 is clamped to the underside of lug 117 of the guard foundation by means of bolt 147 and nut 148, so as to maintain the stop assembly stationary while the work is being moved across the wheel face. Pin 152 is secured in vertical opening 144 in base 141 and is secured therein by nut 157. Rod 159 is located in opening 153 of pin 152 and clamped against collar 156. Carried in opening 161 of rod 159 is a special form of tooth stop which consists of a plain rod 204 held in position by set screw 160 and engages between the teeth of the cutter in such manner that when the auxiliary table is moved past the wheel the cutter will be rocked about the centers the necessary amount to maintain the surface to be ground in the proper relationship to the cutting face of the wheel, it being understood that the operator will, as before, exert

12

sufficient rotative forces upon the tool to maintain it in engagement with stop 204.

Indexing is accomplished by bringing the work beyond the tooth stop then re-engaging the stop with the next tooth to be ground.

In Figure 17 there is disclosed a forming tool 205 carried by a mandrel 206 between the centers of the headstock and tailstock, and is adapted to be ground by a dish form of wheel 17a. In this instance the auxiliary table is again set on zero so as to carry the work in a path at right angles to the wheel axis and a re-arrangement of the parts of the stop mechanism is also utilized. The tool is provided with inclined tooth faces 207, and in order to grind them properly a dish wheel is employed.

Referring to the tooth rest or stop mechanism, base 141 is secured directly to the face of the auxiliary table by bolt 147 and nut 148, and carried by pin 152, inserted through opening 145 in the base, is rod 149. The latter in turn supports rod 159 to which the stop thimble 162 is secured. In this instance the straight stop finger 179 of Figure 11 is secured in place by screw 182 and engages directly behind the tooth being sharpened, head 166 being so oriented that the finger will freely pivot upwardly and allow a new tooth to be presented to the grinding wheel in response to indexing movement of the tool.

In Figures 18 and 19 we have illustrated a modified form of head and tailstock also forming part of the invention. Referring first to Figure 18, the base is of substantially the same form and is secured to the auxiliary table in a manner similar to the tailstock previously described. As seen in Figure 18, the headstock 212 is symmetrical in form, having an enlarged head portion 213 provided with a longitudinal bore 214 communicating with an opening 215. At each end of portion 213 is provided an ear 216, and each ear is split in a vertical plane by a milling cutter, the bottom of the cuts being indicated by the line 217. The ears are provided with screws 218 for tightening the split portions and locking the center 219 in adjusted axial position therein. In this instance the center is shown as made up of a major portion 219 of relatively inexpensive and noncritical material and a hardened alloy insert 221, which forms the actual center.

Referring to Figure 19, the tailstock 223 is made from identically the same pattern and is basically the same in all respects, having an enlarged portion 224, a central bore 225 communicating with an opening 226, and at each end 55 is formed an ear 227, the ears being split by a milling operation along the lines 228. In this instance however center 229 is provided with a longitudinal groove 230 cooperating with a washer 231 to prevent rotation of the center and yet permit free endwise movement.

Center 229 is adapted to be locked in adjusted position by a cap screw 232 threaded into one ear 227, washer 231 being sufficiently thin as to not interfere with the clamping action. Center 65 229 is urged toward work gripping position by a compression spring 233 reacting against a cap 234 securely clamped in the tailstock by a screw 235 cooperating with the other pair of ears 227. The center is adapted to be retracted by a rod 236 projecting through cap 234 and threaded into the center. Cooperating with a lock nut and washer assembly 231 on the free end of rod 236 is the forked end 238 of a lever 239 which is pivoted on a pin 241 carried by a pair of supports 70 242 formed on cap 234.

In the fully released position shown in Figure 19 the forked end of lever 239 lies against the rear face of cap 234, and, when it is desired to retract the center, a handle 243, secured to lever 239 is rocked downwardly, which causes the forked end to move the center to the right, against the action of spring 233.

In Figures 20 and 21 we have illustrated a fine adjustment applied to the auxiliary table, which makes it possible to accurately adjust the table to bring the tool into correct alignment with the wheel even when extremely small angles are involved, without resort to tapping or other expedients.

Provided on the interior of the side webs of the auxiliary table both front and rear are bosses 251 and 252 into which are threaded a pair of adjusting screws 253 and 254 respectively, which may be manually manipulated by cross pin handles or the like. The screws preferably lie in a common horizontal plane closely adjacent the level of the top of main table 23, and cooperate with a stop 255 pivoted on a pin 256 carried by a slide member 257. The latter fits into keyway 25 and has shoulders 258 adapted to be forced into tight engagement with the undersides of the over-hanging portion of the keyway by a set screw 259 threaded into the slide and bearing against the bottom of the keyway. Stop 255 may be pivoted clockwise out of the path of screws 253 and 254 when it is desired to adjust the machine without them, or when the table is adjusted through angles which are too large to permit use of the adjusting screws.

Accordingly, when it is desired to employ the fine adjustment, as for instance when grinding tapered reamers or other tools which may not be true, stop 255 is swung into its full line position; the table is adjusted into the approximate position desired; and the table T-bolt nuts 52 tightened sufficiently to exert a frictional drag. Screw 253 or 254, depending upon the direction the table must be rocked, is then screwed in. This causes the selected screw to engage the stop and force the table to turn about its axis against the resistance of the frictional drag. When the adjustment is complete, nuts 69 are tightened to rigidly lock the auxiliary table in place. In the drawings both screws have, for convenience, been shown engaged with the stop, but it is to be understood that in practice only one screw will be engaged, the other being backed off to allow the table to turn. It is also to be understood that while we prefer to employ a single stop, in combination with front and rear screws, if desired, both screws may be mounted at the front of the table on opposite sides of the pivot and cooperate with separate stops at opposite ends of the table, without departing from the spirit of the invention.

In addition to permitting fine adjustments to be carried out, the novel screw and stop assembly is also advantageous in many other classes of grinding as it makes it possible to set up the parts with the surface to be ground parallel to the travel of the main table, irrespective of shape.

From the foregoing detailed disclosure it is apparent that the invention provides a novel auxiliary table which may be readily installed on the tables of present day surface grinders, for the purpose of converting them to tool and cutter grinders, and which may be adjusted about an axis normal to the table surface to locate the tool or cutter at the proper grinding angle, and also provides novel head and tailstock

assemblies; a tooth rest or stop of novel construction; and guard and guard supporting assemblies which are so designed as to permit a number of different guards to be interchangeably mounted on the support and affords adjustment of the guards into various guarding positions with respect to the wheel, to permit various grinding operations to be carried out without interference from the guards, and at the same time affords maximum protection to the operator.

The invention may be embodied in other specific forms without departing from the spirit or essential characteristics thereof. The present 15 embodiments are therefore to be considered in all respects as illustrative and not restrictive, the scope of the invention being indicated by the appended claims rather than by the foregoing description, and all changes which come within 20 the meaning and range of equivalency of the claims are therefore intended to be embraced therein.

What is claimed and desired to be secured by United States Letters Patent is:

25 1. In a machine tool having a grinding wheel, a slide table and a horizontally reciprocal, work table providing a horizontal, planar work supporting surface below the grinding wheel, an attachment comprising a pilot member; means for 30 securing said pilot member to said work supporting surface; an auxiliary work supporting table overlying said pilot member and resting on said work supporting surface in vertically spaced relationship to said pilot member; pivot means 35 mounting said auxiliary work supporting table for rocking movement about a vertical axis on said pilot member; means on said pivot means for drawing said auxiliary work supporting table down into clamping engagement with said work 40 supporting surface; and means on said auxiliary work supporting table for holding a work piece thereon in position for presentation to said grinding wheel.

2. The combination defined in claim 1 wherein 45 said auxiliary work supporting table is provided with a flat upper face disposed parallel to said work supporting surface and on its underside is provided with at least two transverse ribs, one located each side of said pivot means, said ribs having lower faces located in a common plane and adapted to clampingly engage said work supporting surface in any one of a plurality of adjusted angular positions about said vertical axis.

3. In a grinder having a flat, T-slotted work 50 supporting table, a tool holder comprising a pilot member of disc-like form provided at diametrically opposite points with a pair of securing devices coacting with the T-slot of said work supporting table and operable to secure it in frictional clamping engagement therewith; means, located adjacent each of said securing devices, and projecting into the slot of said work supporting table, for accurately keying said pilot member thereto; an auxiliary work supporting table member overlying said first mentioned work supporting table and having a downwardly projecting portion located either side of said pilot member and resting on said first mentioned work supporting table; a pivot pin, rigidly secured in an opening in one of said members and snugly journaled in an opening in the other member, mounting said auxiliary work supporting table member for limited rocking movement; and clamp means cooperating with said pilot member and said auxiliary work supporting table member

15

for forcing the downwardly projecting portions of the latter into frictional clamping engagement with said first mentioned work supporting table.

4. The apparatus defined in claim 3, wherein said securing devices each have a head located in a recess in the upper side of said pilot member and said clamp means comprises a pair of elements having heads seating in arcuately shaped recesses in the lower side of said pilot member, said recesses being of sufficient depth to dispose said heads below the levels of the upper and lower surfaces of said pilot member.

5. The apparatus defined in claim 3, wherein said clamp means comprises a pair of diametrically spaced elements coacting with arcuately shaped slots in said pilot member, and said securing devices extend through openings between the neighboring ends of said arcuately shaped slots.

6. In a tool grinding apparatus having a flat table reciprocable in a horizontal plane in a cooperative relationship to a grinding wheel, an attachment comprising a pilot member having a cylindrical face and a flat lower face adapted to rest upon said table; means for securing said pilot member to said table; an auxiliary table member overlying said first mentioned table and having depending ribs straddling said pilot member and substantially paralleling the cylindrical face thereof and adapted to rest upon said first mentioned table; means mounting said auxiliary table member for limited rocking movement about a vertical axis on said pilot member, the cylindrical face of the latter having a plurality of graduations; indicia means on said auxiliary table member cooperating with said graduations to indicate the angular position of said auxiliary table member with respect to said pilot member; and means on said pilot member for pulling said auxiliary table member into clamping engagement with said first mentioned table.

7. In a machine tool embodying a table having a flat guiding surface and a longitudinal T-slot, a tailstock comprising a flat base portion seating on said table; an upstanding pedestal rising from said base; a longitudinally directed boss having a bore disposed parallel to said table; a center mounted in one end of said bore for axial movement in the bore and having a tapped opening in its inner end; a stud secured in said tapped opening and extending outwardly through the other end of said bore in spaced relation to the wall of said bore; a coil spring disposed in said bore in surrounding relation to said stud with one end abutting the tapped end of said center; a closure member slidably receiving said stud and secured to said other end of said bore and providing an abutment for the opposite end of said coil spring; a lever pivoted on said closure member and having a bifurcated portion freely receiving the protruding end of said stud; a washer slidably disposed upon the protruding end of said stud and abutting said bifurcated portion of said lever; and a lock nut assembly threaded on the end of said stud for clamping said washer against said bifurcated portion of said lever.

8. In a machine tool, an attachment table having a flat supporting surface, a longitudinally extending T-slot opening into said surface and a squaring surface disposed substantially normal to said supporting surface and parallel to said T-slot and extending from end to end of said table along one side thereof; a centering stock seating only upon said flat supporting sur-

16

face and slideable thereover on a flat base; guiding means at each end of said base seating in and slideable along said T-slot; adjustable means on one side of said base substantially intermediate its ends and bearing against said squaring surface for urging said stock transversely with respect to said table and bringing said guiding means into engagement with one side wall of said T-slot thereby squaring said stock with respect to said table; and means cooperating with said T-slot for frictionally clamping said stock to the supporting surface of said table.

9. In a grinding machine having a table provided with a flat elongated work supporting surface having means for securing work pieces thereto and reciprocable in a horizontal plane, an attachment comprising an auxiliary table of elongated form overlying said supporting surface and extending beyond the ends thereof; said auxiliary table having a plurality of transversely disposed, longitudinally spaced depending portions, the latter being provided along their lower edges with flat clamp faces lying in a common plane and adapted to engage longitudinally spaced areas of said supporting surface; means mounting said auxiliary table for angular movement about a vertical axis while maintaining contact of said depending portions with said supporting surface, wherein said means mounting said auxiliary table for angular movement about a vertical axis comprises a pilot member underlying said auxiliary table; pivot means secured to said auxiliary table and cooperating with said pilot member; and means for securing said pilot member to said flat elongated work supporting surface.
